SAFETY-FUSE.

No. 874,793.

Specification of Letters Patent.

Patented Dec. 24, 1907.

Application filed April 5, 1906, Serial No. 310,045. Renewed May 16, 1907. Serial No. 373,981.

To all whom it may concern:

Be it known that we, JOSEPH SACHS and FRANK D. REYNOLDS, both citizens of the United States, residing at Hartford, in the county of Hartford and State of Connecticut, have invented an Improvement in Safety-Fuses, of which the following is a specification.

Our present invention relates to indicating safety fuse devices as shown and described in our co-pending application Serial No. 307,310, filed March 22nd, 1906, in which instead of merely employing an indicator wire to show the condition of the fuse strip, the indicator wire being directly connected across the terminals of the fuse and either wholly without the casing or partially within and partially outside the casing, or entirely within the casing and having associated therewith means in an aperture and extending through the casing to the visible surface thereof for indicating the condition of the fuse strip,—we employ a wire within the casing of the fuse device which provides therein a shunt circuit across the end caps or fuse strip terminals, and an indicating portion at one end located between one of the said end caps and the adjacent portion of the fuse casing.

In almost all cases where the indicating wire has been directly connected in shunt across the terminals of the fuse device, the indication was obtained by a portion or all of the wire being visible or by separate means affected by the rupture of the indicating wire, thus making a secondary indication.

In carrying out our present invention we produce a means of indication which is direct and positive instead of secondary, and in so doing we employ a tube or casing, end caps or ferrules therefor, a fuse strip electrically connected to the said end caps, a wire electrically connected at one end to one of the end caps and a connection of conducting material preferably of high resistance interposed between the inside of the other end cap and the opposite end of the said wire; and said conducting high resistance connection is preferably of such composition as to be changed, discolored, disrupted or otherwise affected by the current to provide a means of indication.

In the drawing, Figure 1 is a central longitudinal section of a safety fuse embodying

our present invention. Fig. 2 is a plan of the same, showing a portion of one of the end caps broken away. Fig. 3 is a central longitudinal section of a safety fuse embodying a modification of the present invention; and Fig. 4 is a plan of the same.

Referring to the drawings, *a* designates a casing preferably tubular and made of any suitable insulating material. Together with the casing *a* we employ end caps *b* adapted to fit over the respective ends thereof and also fuse strip terminals *c* electrically connected to the said end caps, together with a fuse strip *d* extending between and electrically connected with the said fuse strip terminals.

The outer surface of the tube *a* at one end thereof may be provided with a recess *2*, so placed that the greater portion thereof extends under and lies beneath the body of one of the end caps *b* and within this recess and between the body of the end cap *b* and the adjacent portion of the tube *a*, we employ an indicating connection *3* preferably made solely of carbon, graphite or other material of low conductivity, or a mixture of the same and a small quantity of a suitable explosive or combustible material, such as gunpowder. The material of which this connection is made may be either in loose or solid condition and applied in any suitable manner.

e designates a wire electrically connected at one end with one of the end caps *b* and is passed longitudinally through the tube *a*, through a slit or notch *4* provided in the opposite end of the tube *a*, and into the recess *2*, the other end of the said wire being at the base of the recess with the indicating connection completing the circuit to the inside of the end cap.

It will be understood that the wire *e* may be of any suitable metal and need not necessarily be of high resistance, since it is connected in series with the indicating connection *3* which is of the necessary resistance to form with the wire *e*, the required shunt around the main fuse wire. We are therefore enabled to make this wire *e* of materially greater section and hence more substantial than has heretofore been possible where the indicating wire embodied the entire resistance of the shunt circuit. The connection *3* is placed in the recess *2*, completely filling the same and extending be-

yond the edge of the end cap and coming flush with the surface of the tube *a*, and that portion of the connection extending beyond the edge of the ferrule may be covered or 5 partially covered with a drop of white paint 6 or other material which becomes discolored upon the rupture of the fuse to indicate such a condition, or the connection may fill only a portion of the recess in the tube and extend 10 to the edge of the end cap or only part way to the said edge, and when the connection does not extend beyond the edge of the end cap, its composition is preferably of an explosive or disruptive nature.

15 Instead of placing the material forming the connection within a recess as indicated in Figs. 1 and 2, we may make up this member independently into a strip or plate indicated at 5, Figs. 3 and 4, and made of paper 20 or cloth or other similar material impregnated with a suitable mixture of combustible and high resistance conducting material and adapted to be interposed between the inside of an end cap and one end of the 25 wire *e* as illustrated. We preferably employ a filling of an insulating material in a loose condition indicated at *f*.

In operation after the blowing of the fuse wire, the current passes through the indicating 30 connection by way of the wire *e* and the heating of the connection 3 by the current, causes it to burn, disrupt, discolor, explode or otherwise indicate directly or indirectly, the blowing of the fuse.

35 A notable advantage of our indicator will be found in the fact that it may be of very high resistance and made to operate with extremely small current, hence, it can be used with fuses of small carrying capacity 40 without affecting their normal rating and due to its direct operation, failure to indicate is practically eliminated.

45 By locating the indicating connection within the end cap, it is protected from injury and when it is not desirable to cut the end of the tube to provide the recess, it can be provided in the end cap.

It will be noted in the construction shown 50 in the drawings that the end caps act as contact terminals for the completed fuse device but we do not limit ourselves to this specific arrangement as it will be understood that any other form of external contact terminal may be used either in conjunction with end 55 caps or in any other suitable manner. We also do not limit ourselves to the particular manner in which the wire *e* is connected at the non-indicating end nor do we wish to limit ourselves to the particular manner in 60 which the indicating connection is made between the other end of said wire and one end cap.

We claim as our invention:

1. A safety fuse comprising a tube, end 65 caps therefor, a fuse strip within the tube, a

wire electrically connected at one end to one of the said end caps, and indicating means electrically interposed between the other end of said wire and the other end cap.

2. A safety fuse comprising a tube, end 70 caps therefor, fuse strip terminals electrically connected to the said end caps, a fuse strip extending between and electrically connected with the said fuse strip terminals, a wire electrically connected at one end to one of the said end caps, and an indicating means 75 electrically interposed between the other end of the said wire and the other end cap.

3. A safety fuse comprising a tube, end 80 caps therefor, a fuse strip, a wire electrically connected at one end to one of the said end caps, and an indicating connection interposed between and electrically connected to the other end cap and the other end of said wire.

4. A safety fuse comprising a tube, end 85 caps therefor, fuse strip terminals electrically connected to said end caps, a fuse strip extending between and electrically connected with the said fuse strip terminals, a wire electrically connected at one end to one of the said end caps, and an indicating connection 90 interposed between and electrically connected to the other end cap and the other end of the said wire.

95 5. A safety fuse comprising a tube provided with a recess in its outer surface and at one end thereof, end caps for the said tube, a fuse strip, a wire connected at one end to one of the said end caps, and an indicating connection within the said recess in the casing, and interposed between the other end cap and the opposite end of the said wire.

100 6. A safety fuse comprising a tube provided with a recess in its outer surface at one end 105 thereof, end caps for the said tube, fuse strip terminals electrically connected to the said end caps, a fuse strip extending between and electrically connected with the said fuse strip terminals, a wire electrically connected at 110 one end to one of the said end caps, and an indicating connection within the said recess in the casing and interposed electrically between the other end cap and the opposite end of said wire.

115 7. A safety fuse comprising a tube, end caps therefor, a fuse strip, a conductor connected at one end with one of said end caps, and means interposed between the other end cap and the opposite end of the said conductor for indicating the blowing of the fuse.

120 8. A safety fuse comprising a tube, having a recess in its outer surface at one end thereof, end caps for said tube, the recess in the tube being of such an extent as to lie beneath the 125 body portion of one of the end caps and to extend beyond the edges of the same, a fuse strip, a conductor connected at one end to one of the end caps, and means within said recess and interposed between the other end 130

cap and the opposite end of the said conductor for indicating the blowing of the fuse.

9. A safety fuse comprising a tube having a recess in its outer surface at one end thereof, 5 end caps for said tube, the recess in the tube being partly beneath one of the end caps and extending beyond the edge of the same, a fuse strip, a conductor connected at one end to one of the end caps, and an indicating 10 connection within said recess and electrically interposed between the other end cap and the opposite end of the said conductor.

10. A safety fuse comprising a tube having a recess in its outer surface at one end there- 15 of, end caps for the said tube, the recess in the tube being partly beneath one of the end caps and extending beyond the edge of the same, a fuse strip, a conductor connected at one end to one of the end caps and an indicating 20 connection of resistance material filling said recess and electrically interposed between the other end cap and the opposite end of the said conductor.

11. A safety fuse comprising a tube having 25 a recess in its outer surface at one end thereof, end caps for said tube, the recess in the tube being of such an extent as to lie beneath the body portion of one of the end caps and to extend beyond the edge of the same, a fuse 30 strip, a conductor connected at one end to one of the end caps, and an indicating connection of a mixture of combustible and re- 35 sistance material within said recess and electrically interposed between the other end cap and the opposite end of the said conductor.

12. A safety fuse comprising a tube, end 40 caps therefor, a fuse strip within the tube, a wire electrically connected at one end to one of said end caps, and indicating means elec- trically interposed between the other end of said wire and the other end cap and located between the inside of the end cap and the tube.

13. A safety fuse comprising a tube, end caps for said tube, there being a recess be- 45 tween one of said end caps and one end of said tube, a fuse strip within the tube with its ends electrically connected to the end caps, a conductor connected at one end to one of said end caps, and an indicating connection 50 electrically interposed between the other end cap and the opposite end of said conductor and located in the recess but having a portion extending visibly beyond the edge of the end cap. 55

14. A safety fuse comprising a tube, end caps therefor, a fuse strip within the tube, a conductor electrically connected to one end of said end caps, and an indicating connec- 60 tion of conducting material inside of the other end cap and between it and the other end of said conductor, a portion of said connection being visible.

15. An indicator for inclosed safety fuse consisting of a wire electrically connected at 65 one end to one terminal of said fuse and having an indicating connection interposed between its other end and the other terminal of said fuse, said connection being within the inclosing structure of the fuse. 70

16. A safety fuse comprising a tube, end caps therefor, a fuse strip within the tube, a wire electrically connected at one end to one of said end caps, and an indicating connection of a mixture of combustible and resistance mate- 75 rial electrically interposed between the other end of said wire and the other end cap and located between the inside of the end cap and the tube.

Signed by us this 28th day of March 1906. 80
